US00D507937S

(12) **United States Design Patent** (10) Patent No.: **US D507,937 S**
Dais et al. (45) Date of Patent: **** Aug. 2, 2005**

(54) **SHORT THREADED STORAGE CONTAINER BASE**

(75) Inventors: **Brian C. Dais**, Saginaw, MI (US); **Charles L. Lasky**, Grafton, WI (US); **Douglas J. Carpiaux**, Milwaukee, WI (US); **David H. Roland**, Pella, IA (US)

(73) Assignee: **S. C. Johnson Home Storage, Inc.**, Racine, WI (US)

(**) Term: **14 Years**

(21) Appl. No.: **29/203,907**

(22) Filed: **Apr. 22, 2004**

(51) LOC (8) Cl. **07-07**

(52) U.S. Cl. **D7/602; D7/615; D9/428**

(58) Field of Search **D7/602, 612-629, D7/538-542; D9/414, 424-432; 220/4.21, 780-806, 309.1, 367.1, 376, 377; 229/406, 902-906**

(57) **CLAIM**

The ornamental design for a short threaded storage container base, as shown and described.

DESCRIPTION

FIG. 1 is a perspective view of the container base;
 FIG. 2 is front view of the container base;
 FIG. 3 is a side view of the container base;
 FIG. 4 is a top view of the container base; and,
 FIG. 5 is a bottom view of the container base.

The rear of the container base is identical to, and a mirror image of, the front of the container base depicted in FIG. 2. The side of the container base opposite to the side depicted in FIG. 3 is identical thereto, and a mirror image thereof.
